DISPOSABLE CANNULA

Frank J. Rychlik, Northbrook, Ill., assignor to Illinois Tool Works Inc., Chicago, Ill.

Filed Jan. 4, 1971, Ser. No. 103,932

Term of patent 14 years

Int. Cl. D24—02

U.S. Cl. D83—12

FIG. 1 is a perspective view of a disposable cannula showing my new design.

FIG. 2 is a side elevational view of the disposable cannula;

FIG. 3 is a side elevational view of the disposable cannula of FIG. 2 as viewed from the opposite side;

FIG. 4 is an end view of the device shown in FIG. 1 as viewed from the proximal end; and

FIG. 5 is a plan view as viewed from the top side of the device shown in FIG. 3.

I claim:

The ornamental design for a disposable cannula, as shown.
